UNITED STATES PATENT OFFICE.

WILLIS A. COOK, OF REPUBLIC, WASHINGTON, ASSIGNOR OF ONE-HALF TO ALEX. MCKAY, OF REPUBLIC, WASHINGTON.

DRILL-PULLER.

1,295,700.

Specification of Letters Patent. Patented Feb. 25, 1919.

Application filed May 15, 1918. Serial No. 234,749.

To all whom it may concern:

Be it known that I, WILLIS A. COOK, a citizen of the United States, residing at Republic, in the county of Ferry and State 5 of Washington, have invented new and useful Improvements in Drill-Pullers, of which the following is a specification.

This invention relates to an improved drill pulling device and resides in the construction, combination and operative arrangement of parts set forth in the following specification and pointed out with particularity in what is claimed.

In the drawings,

15 Figure 1 is an elevation illustrating the application of the improvement.

Fig. 2 is a plan view of the grip block.

Fig. 3 is a plan view of the puller arm or member.

20 It is the object of the present invention to dispense with the hand method of pulling drills, to save the time and labor exerted thereby and to provide an extremely simple but thoroughly efficient manner whereby a 25 stuck drill may be removed in an easy and efficient manner at a small amount of time and with a comparatively slight amount of labor upon the part of the miner.

In Fig. 1 of the drawings the numeral 5 30 designates a drill bit which is supposed to have been stuck in a hole. The numeral 6 designates a "Stopper" drilling machine actuated by compressed air power. When the bit 5 is stuck the chuck 7 of the drilling 35 machine 6 is actuated to release the bit 5. A second bit 8 is then arranged in the chuck of the drilling machine and is actuated by the drilling machine so that the same is received in a comparatively shallow hole in 40 the stratum mine in which the bit 5 is stuck. The bit 8 is not an addition to the miner's kit but may be one of the bits usually used. The bit 8 is comparatively short, say about two feet long and is bored in the stratum 9 45 only a short distance away from the bit 5. When the bit 8, which provides the fulcrum member for the improvement, is inserted, say about six inches in the stratum 9 the drilling machine 6 is removed therefrom 50 and is positioned a slight distance to one side of the fulcrum bit 8, the drilling machine 6, the fulcrum 8 and the stuck bit 5 being arranged in parallelism. In the drilling machine 6 is now secured a pulling arm 55 10, the same including a shank 11 corre-

sponding in shape to the bits so that the same may be properly engaged by the chuck 7. The shank 11, at the outer end thereof is provided with an offset portion forming with the same what I will term a head and 60 which is designated by the numeral 12. This head, at the outer end thereof is provided with an opening 13 of a shape corresponding to the cross sectional shape of either of the bits 5 or 8 so that the bit 8 65 will freely slide through the opening 13, more properly speaking the member 11 will side over the fulcrum bit 8 when the drilling machine is operated, and will be guided by the said fulcrum member 8.

70 The head 12, at a suitable distance inward of the opening 13 is provided with an additional opening 14 through which passes one of the end links of a chain 15, the said end link being engaged by a suitable pin 16 that 75 is disposed transversely of the slot 14 resting upon the outer face of the head 12.

75 On the lower end of the fulcrum bit 8 is arranged a socket 17 formed on one end of a slotted member, and between the arms 18 80 provided by the slot in the said member is pivotally secured, as at 19 a wheel 20. Around this wheel the chain 15 is trained, and the free end of the chain is passed through an opening 21 in one end of what 85 I will term a grip block 22. The referred to end of the chain 15 is engaged by a pin 23, passing through the said link and straddling the opening 21. The grip block is provided with an opening 24 providing 90 centrally communicating right angular passages, corresponding to the cross sectional shape of the bit 5, through which openings the said bit 5 is passed. The block 22 is tilted or canted so that the walls of the 95 opening 24 will firmly grip the surfaces of the bit 5. The valve 25 of the "Stopper" drilling machine is turned to admit air through the flexible tube 26 for actuating the mechanism to move the arm 10 outwardly toward the stratum. 9. This, of course, pulls on the chain 15, causing the same to travel around the wheel 20, causing the grip block to pull upon the bit 5 to withdraw the same from its opening in the stratum. It will be apparent that the grip block 22 may be adjusted to engage at different points on the bit 5, and from the foregoing description, when taken in connection with the drawings, the simplicity 100 105 110

and advantages of the construction will be apparent without further detailed description.

Having thus described the invention, what I claim is:

- 5 1. In a means for pulling a stuck bit from a hole, the combination with a drilling machine, an arm in said machine designed to be moved outwardly therefrom, said arm 10 having a head, a fulcrum member receiving the head and providing a guide for the arm, a wheel on the fulcrum member, a grip block engaging the drill and a flexible element secured to the block, guided around 15 the wheel and connected to the head of the arm.
2. In a device for the purpose set forth, the combination with a drilling machine, of a fulcrum member adapted to be removably 20 secured between a bit to be pulled and the drilling machine, an arm movable through the drilling machine having an angle portion providing a head, and said head having an opening receiving the fulcrum member, a
- 25 wheel removably connected with the fulcrum member, a grip block having an opening therein receiving the bit and designed to be canted to frictionally contact with the bit, and a flexible element secured to the head of the arm and to the grip block and 30 trained around the wheel.
3. In a means for pulling a stuck bit from a hole, the combination with a drilling machine, an arm having an angle end and a shank received in the machine and longitudinally movable thereby, said arm having an opening, a fulcrum member received in this opening, a wheel on said fulcrum member, a grip block having an opening thereon 35 designed to receive the bit to be pulled, and 40 to be canted to frictionally engage with said bit, and a flexible element associated with said grip block trained around the wheel of the fulcrum member and connected with the arm.

45 In testimony whereof I affix my signature.

WILLIS A. COOK.
